TEXTILE FABRIC

William M. Thomson, Senoia, Ga., assignor to Southern Mills, Inc., Atlanta, Ga., a corporation of Georgia

Application October 12, 1955, Serial No. 38,339

Term of patent 3½ years

(Cl. D92—1)

The figure is a plan view of a textile fabric showing my new design.

My design comprises a regular series of broken ovals formed by dark exposed transverse threads, a smaller oval-like element appearing in the center of each oval, and a row of similar smaller oval-like elements arranged between the rows of large ovals and in off-set relationship thereto, all as shown.

I claim:

The ornamental design for a textile fabric, substantially as shown and described.
